CONTROL MECHANISM

Lewis R. Smith and William A. Minkler, Pittsburgh, Pa., assignors to Westinghouse Electric & Manufacturing Company, East Pittsburgh, Pa., a corporation of Pennsylvania

Application February 15, 1934, Serial No. 711,324

9 Claims. (Cl. 236—44)

Our invention relates to a control system for air conditioning apparatus and it has for its object to provide an improved system.

A further object of our invention is to provide 5 a control system, for a plurality of air treating devices receiving an air treating medium from a common source, which operates so that the number of devices which are connected to said source is always in excess of a predetermined 10 number.

While not necessarily limited thereto, our invention is particularly adapted to control relatively small air conditioning devices commonly referred to as "room conditioners". These devices usually include an evaporator or cooling coil for cooling air, a humidifying device and a fan for translating air to be treated. These elements are usually carried by a casing and form a unitary structure.

20 It is frequently desirable to operate a number of these devices for cooling air from a single refrigerating machine and, therefore, the number of devices that are connected to it at one time should be maintained above a predetermined 25 minimum for efficient operation and to prevent frosting of the evaporator by reason of reduced temperature.

According to our invention, we provide a plurality of air cooling devices which are operated 30 in groups. A switch is provided for controlling the operation of the refrigerating machine and the flow of refrigerant to all devices in a group, one such switch being preferably provided for each cooling device. A second switch is provided 35 for each device for control of the fans, and all of the fan switches in a group are so interconnected that all of the fans in the group may be controlled from any switch. In order that circulation of air is assured at all times that cooling is effected, 40 we prefer to interconnect the first and second-mentioned switches so that the former are energized only when at least one of the latter are closed to operate the fans.

When the room conditioners are provided with 45 humidifying means, they may be operated in the same manner as when cooling; that is, when a switch is closed to effect humidification, all fans and humidifying devices in the group operate to circulate and humidify the air. Means are preferably provided whereby the fans of a group may be operated for ventilation without the cooling or humidifying means being operative. If desired, automatic control of a group of devices in accordance with conditions of the air in the space served thereby may be effected by providing suit-

able instruments, such as, thermostats or humidostats, in the space and connecting the same in the electrical circuits of the group of devices.

These and other objects are effected by my invention as will be apparent from the following description and claims taken in accordance with the accompanying drawing, forming a part of this application, in which:

Fig. 1 diagrammatically shows a plurality of air conditioning devices having our improved 10 control system applied thereto.

Fig. 2 is a straight line or schematic diagram of the control system.

The air conditioning devices are preferably operated in groups, which may respectively serve 15 a plurality of spaces, one of which is generally shown at 10. We have shown but one group of devices as the other groups are identical with the one shown; however, the circuits leading to the other groups are indicated in the drawing. 20 The group indicated at 10 includes first and second air conditioning devices 11 and 12, each of which includes an evaporator or air cooler 13, a humidifying device 14 and a fan 15 for translating air to be treated. These elements are disposed within a cabinet structure 16 which has an inlet opening 17 through which air to be treated is admitted and an outlet opening 18 through which the treated air is discharged. The fan 15 is preferably carried by the cabinet 16, adjacent 30 the inlet opening 17, and functions to draw air from the space 10 and force it through the cabinet 16 for treatment and then discharging it to the space 10 through the opening 18.

It will be seen that we have shown the openings 17 of both devices 11 and 12 in communication with the space 10 so that the air therein is recirculated but it will be understood that fresh air from the outside atmosphere may be treated in which case the inlet openings 17 would communicate with the exterior of the building. The fans 15 are preferably driven by electric motors 19.

The humidifying devices 14 are supplied with water from a pipe 21 which connects to a suitable source. Valves 22 are connected in the pipe 45 21 for controlling the flow of water to the humidifying devices 14 and are preferably operated by solenoids 23. The humidifying devices 14 include nozzles 24 through which water is discharged in a finely divided condition or mist into the air propelled by the fan. The body of air passing through the mist readily vaporizes and absorbs moisture therefrom. Water discharged by the nozzle 24 which is not vaporized and taken up by the air falls to the bottom of the cabinet

16 and is drained away through a conduit 25 to a point of discharge. It will be understood that, during winter operation, the air in the space 10 is heated either by some extraneous means or 5 by heaters 26 disposed within the cabinets 16. The heaters 26 are of conventional construction and are supplied with a heating medium in any well known manner.

The air coolers or evaporators 13 are supplied 10 with refrigerant for absorbing heat from the air to be treated by a refrigerating machine 27. The latter may be of any suitable type but we prefer and show a machine of the compressor-expander type which includes a compressor 28, driven by 15 a motor 29, and a condenser 31. The evaporators 13 include expansion devices, preferably valves 32, for effecting a reduction in pressure of the refrigerant supplied to the evaporators 13. As these valves 32 are of well known construction, 20 no further description of them is deemed necessary.

The cooling system operates on the well known compression-expansion cycle in which gaseous or 25 spent refrigerant is withdrawn from the evaporators 13 by the compressor 28 through a branched conduit 33. It is then compressed by the compressor 28 to a relatively high pressure and is discharged into the condenser 31 in which it is cooled and condensed. The liquid refrigerant is then conveyed by a conduit 34 to the expansion valves 32 which reduces the pressure of 30 the refrigerant to that maintained in the evaporator by the suction of the compressor. When subjected to the relatively low pressure in the 35 evaporators 13, the refrigerant vaporizes and abstracts heat from the evaporator in a well known manner. Air which is conveyed in heat-exchanging relation with the cold evaporator 13 is cooled therein before it is delivered to the space 10. The 40 flow of refrigerant to the evaporators 13 may be controlled, preferably by a valve 35, connected in the conduit 34, and operated by a solenoid 36.

The conduit 34 is provided with branches 34a and 34b, having valves 35a and 35b, respectively, 45 for supplying liquid refrigerant to additional groups of air conditioning devices which are identical with the devices 11 and 12, and the conduit 33 is provided with branches 33a and 33b for withdrawing vaporized refrigerant therefrom.

50 The various groups of air conditioning devices are supplied with current from a source of current (not shown) through conductor L¹ and L² and circuits 37, 38, and 39. The circuits 38 and 39 run to said additional groups of air conditioning devices and are identical with the circuit 37; therefore the complete circuit diagram for these 55 circuits is not shown. The circuits 37, 38, and 39 supply relatively low voltage current for the operation of the various fan motors 19 and for the control circuits. The motor 29 however is 60 preferably supplied with higher voltage current through conductors 41 in which contacts 42 of a relay 43 are connected. The latter also includes a solenoid 44 for operating the contacts 42.

65 Reference will now be had to the control circuits shown in connection with the air conditioning devices 11 and 12. The air conditioning device 11 has a plurality of switches 45, 46, and 47 associated therewith and the device 12 70 includes similar switches 48, 49, and 51. These switches are mounted adjacent to their respective devices and are preferably carried by the cabinets 16 thereof. The switches 45 and 48 control the supply of refrigerant to the evaporators 13 and the operation of the refrigerating

5 machine 27. The switches 46 and 49 control the operation of the humidifying devices 14 and the fans 15. Switches 47 and 51 control the operation of the fans 15.

If automatic control of the temperature of the air in space 10 to be effected, is a thermostat 52 10 is disposed in the space 10. The thermostat 52 operates switches 53 and 54 which respectively control the operation of the valve 35 and the relay 43. The humidity of the air in space 10 may be 15 controlled by a humidostat 55 which includes a switch 56 connected in circuit with the solenoids 23. The thermostat 52 maintains its switches 53 and 54 open when the temperature of the air in the space 10 is below a predetermined degree and the humidostat 55 maintains its switch 56 open when the humidity of the air is above a predetermined amount. As these instruments are well known in the art, no further description of them 20 will be given.

The conductors which connect the various control elements are clearly shown in the drawing and will be referred to in the description of operation which follows. For winter operation, one of the switches 46 or 49 will be closed to render the 25 fans 15 and the humidifying devices 14 operative. The circuit for the fans may be traced from line conductor L¹, conductor 57 of circuit 37, one pole of switches 46 or 49, conductor 58, fans 19 of the devices 11 and 12, conductor 59 of circuit 37 to the 30 line conductor L². The circuit for the solenoids 23 which control valves 22 in the water supply line 21 may be traced from line conductor L¹, conductor 57, the other pole of switches 46 or 49, conductor 61, switch 56 of the humidostat 55, conductor 62, solenoids 23, conductor 59, to the other line conductor L².

It will be understood, that, during winter operation, the air in the space 10 will be heated, for example, by the heaters 18. If the humidity of the 40 air is below a predetermined amount, the humidostat switch 56 is in its closed position. Therefore, current flows through the circuit described above which includes the solenoids 23. The valves 22 are maintained open thereby so that water from 45 the supply pipe 21 flows to the humidifying devices 14 and is sprayed by the nozzles 24 into the air being translated by the fans 15. Moistened air delivered to the space 10 increases its humidity; and, when a predetermined amount is attained, the humidostat 55 opens its switch 56 for deenergizing the solenoids 23. The valves 22 are therefore closed and humidification of the air terminated. The fans 15 continue to operate for 50 ventilation as the circuit thereof is independent of the humidostat switch 56. It will be apparent that the operation described will be the same, regardless of which switch 46 or 49 is closed.

The fans 15 may be operated at any time for 55 ventilation, without any treatment of the air whatever, by closing switches 47 or 51. These switches are connected across conductors 57 and 58 and parallel the pole of switch 46, and of switch 49, which is included in the fan circuit previously described.

During warm weather, when cooling is to be effected, switch 47 or 51 and switch 45 or 48 are closed. Ordinarily, the switches which are closed are those associated with one air conditioning device, for example, switches 45 and 47 of the device 11.

We have shown in the drawing an arrangement whereby a fan switch 47 or 51 must be closed before a cooling switch 45 or 48 is energized, or rendered operable. The purpose of this arrangement 75

ment is to assure operation of the fans 15 at all times that cooling is effected. It will be apparent that this result may also be obtained in the same manner as shown in connection with the humidification switches 46 and 49.

Referring to the arrangement shown on the drawing, assume that the switches 45 and 47 are closed and that the temperature of the air in the space 10 is above a predetermined degree to be maintained. The switches 53 and 54 of the thermostat are therefore closed. A fan circuit is completed from the line conductor L¹, conductor 57, switch 47, conductor 58, fan motors 19, conductors 59 to the other line conductor L². A circuit is also completed from the energized conductor 58, switch 45, a conductor 64, switch 53, conductor 65, solenoid 36, conductor 59, to the line conductor L². Another circuit is completed from the energized conductor 64, jumper 66, the second pole of switch 45, conductor 67, switch 54, conductor 68, solenoid 44, to the line conductor L².

Energization of the solenoid 36 opens the valve 35 to admit refrigerant to the evaporators 13 and energization of the solenoid 44 closes the switches 42 to effect operation of the refrigerating machine 27. Air discharged by the fans 15 is cooled by the evaporator before it is delivered to the space 10. When the temperature of the air in the space 10 has been depressed to the desired degree, the thermostat 52 operates to open its switches 53 and 54, thereby deenergizing the solenoid 36 and 44. Deenergization of the former terminates the flow of refrigerant to the evaporators 13 and deenergization of the latter stops operation of the refrigerating machine 27. It will be seen that the fans continue to operate for ventilation as their circuits are independent of the thermostat switches 53 and 54 and the switch 47 is closed.

The other groups of air conditioning devices, (not shown) which are served by the circuits 38 and 39, are operated in the same manner as the group serving space 10. All groups effect operation of the relay 43 as the conductor 68 is common to all of the groups.

From the above description, it will be seen that we have provided a control mechanism whereby a predetermined minimum refrigerating load is imposed on the refrigerating machine at all times that it is in operation. For example, assume that the refrigerating machine 27 has a capacity equal to six cooling devices similar to the cooling device 11 or 12 and that it is not desirable to operate the refrigerating machine with a load less than one-third of its capacity. With the above described control mechanism, there are at least two cooling devices in operation whenever the refrigerating machine 27 is in operation, thereby assuring the predetermined minimum load on the refrigerating machine. This load is sufficient to provide a suction pressure corresponding to a temperature above the freezing point, thereby avoiding frosting of the evaporator.

While we have shown our invention in but one form, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. In a control system for air conditioning apparatus, the combination of a plurality of groups of air cooling devices, a refrigerating machine for providing a supply of refrigerant for

the devices, a plurality of electrically-operated valves for respectively controlling the flow of refrigerant from said refrigerating machine to the groups of devices, switches associated with each device for controlling the operation of said refrigerating machine, and connections between the switches of each device in a group and the valve associated with the group for effecting control of the latter by any of the former.

2. In a control system for air conditioning apparatus, the combination of a plurality of groups of air cooling devices, a fan associated with each device for translating air to be cooled, a refrigerating machine for providing a supply of refrigerant for the devices, a plurality of electrically-operated valves for respectively controlling the flow of refrigerant from said refrigerating machine to the groups of devices, fan switches associated with the devices for controlling the operation of their fans, connections for paralleling the switches of each device in a group, whereby closure of one switch initiates operation of all of the fans in the group, cooling switches associated with the devices for controlling the operation of said refrigerating machine, connections between the cooling switches of each device in a group and the valve associated with the group for effecting control of the latter by any of the former.

3. In a control system for a plurality of air conditioning devices, each of which includes, an air cooler, a humidifier and a fan for translating air to be treated, means providing a supply of liquid for the humidifiers, electrically operated valves for respectively controlling the flow of liquid from the last mentioned means to the humidifiers, a refrigerating machine for providing a supply of refrigerant for the air coolers, electrically operated valve means associated with each group of devices for controlling the flow of refrigerant from the refrigerating machine to the air coolers of the group of devices, a plurality of switches associated with each device and including, a humidifying switch for controlling the operation of the humidifier and the fan, a cooling switch for controlling the operation of the refrigerating machine and the refrigerant valve, and a fan switch for controlling the operation of the fan and for rendering the cooling switch operable and inoperable, and connections for paralleling the cooling, humidifying and fan switches of one device in a group with corresponding switches of the other devices in the group, whereby operation of an electrically operated refrigerant valve means serving a group of devices and the refrigerating machine is effected by closure of a fan switch and a cooling switch associated with said group of devices, operation of all electrically operated liquid valves and fans associated with the group is effected by closure of any humidifying switch associated with the group, and operation of all fans associated with the group is effected by closure of any fan switch associated with the group.

4. In a control system for air conditioning apparatus, the combination of a plurality of groups of air treating devices for respectively treating the air in a plurality of spaces, means providing a supply of air treating medium for said devices, a plurality of electrically-operated valves for respectively controlling the supply of medium from said supply means to the groups of devices, means responsive to a condition of the air in one of said spaces for controlling the operation of the supply means and the valve asso-

- ciated with the devices serving said space, switches associated with each of the devices and connections between the switches associated with a group of devices and the condition responsive means associated with the group, whereby the latter means may be rendered operable and inoperable by any of the switches connected therewith.
5. In a control system for air conditioning apparatus, the combination of a plurality of groups of air cooling devices for respectively cooling the air in a plurality of spaces, a refrigerating machine for providing a supply of refrigerant for said air cooling devices, an electrically operated valve for controlling the flow of refrigerant from said machine to each group of devices, means responsive to the temperature of the air in a space for controlling the operation of the refrigerating machine and the valve associated with the group of devices serving said space, a switch associated with each device in said group, and connections between each of the switches and the temperature responsive means whereby the latter may be rendered operable and inoperable by any of the switches.
10. 6. In a control system for air conditioning apparatus, the combination of a plurality of groups of air humidifying devices, each of which includes a fan for translating air to be humidified, a source 15 of liquid for said devices, electrically operated valves for respectively controlling the flow of liquid from said source to the air humidifying devices, switches associated with each device for controlling the operation of the valves and fans, and connections between the switches of all the 20 devices in a group for effecting operation of all valves and fans in the group when one of the switches in the group is moved to its closed position.
25. 7. The combination of a plurality of groups of humidifiers, for respectively humidifying the air in a plurality of spaces, a source of liquid for said 25 humidifiers, a plurality of electrically operated valves for respectively controlling the supply of liquid from said source to the humidifiers, humidostats disposed within the said spaces for respec-
- tively controlling the operation of the valves associated with the spaces, a switch associated with each humidifier, connections between the humidostat, switches and valves of the humidifiers serving one of the spaces whereby the former may be rendered operable and inoperable by any of its associated switches, a second switch associated with each humidifier, connections between the second switches of all of the humidifiers in the group and the fans thereof whereby all of the latter may be controlled by any of the former and means for operating the first and second switches of each humidifier simultaneously.
10. 8. In a control system for air cooling apparatus, the combination of at least three air cooling devices, a refrigerating machine for providing a supply of refrigerant for the air cooling devices, and means for controlling the operation of the refrigerating machine and for selectively controlling the supply of refrigerant to the air cooling 15 devices, said last-mentioned means effecting supply of refrigerant to at least two air cooling devices at all times that operation of the refrigerating machine is effected.
15. 9. In a control system, the combination of a plurality of air conditioning devices, each of which includes an air cooler, a humidifier and a fan for translating air to be conditioned, a refrigerating machine for providing a supply of refrigerant for said air coolers, a source of liquid 20 for said humidifiers, means for controlling the operation of the refrigerating machine and for selectively controlling the supply of refrigerant to the air coolers so that at least two air coolers are effective at all times that operation of the 25 refrigerating machine is effected, means for controlling the operation of the humidifiers so that at least two of the same are effective at all times when they are connected to said liquid source, means for effecting operation of the fans at all 30 times that their associated air coolers or air humidifiers are effective and means for effecting operation of at least two fans for ventilation independently of the last-mentioned means.

LEWIS R. SMITH.
